ALONZO RUNNION, OF SPENCER, WEST VIRGINIA, ASSIGNOR OF ONE-HALF TO LEWIS.
S. GOFF, OF SPENCER, WEST VIRGINIA.

WELL-DRILLING APPARATUS.

1,235,385.

Specification of Letters Patent. Patented July 31, 1917.

Application filed August 17, 1916. Serial No. 115,465.

To all whom it may concern:

Be it known that I, ALONZO RUNNION, a citizen of the United States, residing at Spencer, in the county of Roane and State 5 of West Virginia, have invented a new and useful Well-Drilling Apparatus, of which the following is a specification.

The present invention relates to an apparatus for use in drilling wells, and has for 10 an object to provide a jack for attachment to a well drilling apparatus, to permit the use of a high speed engine, such as an internal combustion engine, in drilling wells.

The above object is accomplished, in the 15 present invention, by the provision of a drive part or member, connected to and continuously driven by the high speed engine, a driven part or member which is connected to the usual walking beam employed for 20 supporting the well drilling tools, and a loose connection between the two parts or members for actuating the driven part by the driving part to lift the well drilling tools, and to permit the racing of the driven 25 part to drop or jar the tools in the hole for drilling the well. The loose connection according to this invention, is adjustable for regulating the length of the stroke of the tools, and is also yieldable to absorb shock 30 incident to the taking up of the driven part by the drive part, and also by the checking of the movement of the driven part at the end of the stroke.

The invention will be best understood 35 from a consideration of the following detailed description, taken in connection with the accompanying drawing forming part of this specification, with the further understanding that while the drawing shows a 40 practical form of the invention, the latter is not confined to strict conformity with the showing of the drawing, but may be changed and modified so long as such changes and modifications come within the 45 scope of the appended claims.

In the drawing:

Figure 1 is a side elevation of a well drilling apparatus having the improved jack applied thereto, the walking beam being in 50 the position it assumes when the tools are lowered in the well.

Fig. 2 is a detail enlarged section, taken

vertically and longitudinally through the improved jack, the parts being shown in position immediately after the driven member has completed its stroke.

Fig. 3 is a similar view, showing the parts in position for lifting the tools.

Fig. 4 is a side elevation of the improved jack, showing the connecting rod attached thereto, and in position immediately prior to the jarring of the tools.

Fig. 5 is a transverse section, taken on the line 5—5 of Fig. 2.

Referring to the drawing, 10 designates 65 a suitable base provided with a post 11, on which is mounted a walking beam 12, adapted to be connected at one end to the usual well drilling tools, not shown, by means of a link 13, and having a connecting rod 14 70 on its opposite end.

The base 10 has a power shaft 15 suitably mounted thereon, which is adapted to be turned by any suitable source of power, such as a high speed engine, particularly 75 of the internal combustion type. The shaft 15 carries a pulley 16 over which passes a belt 17, the latter engaging over a balance-wheel 18. This balance-wheel 18 is fixed upon a shaft 19, adapted to be continuously 80 turned with the balance-wheel.

The present invention relates particularly to an improved jack or device for connecting the shaft 19 to the rod 14. A driven member 20 is mounted loosely on the shaft 19, and 85 is in the form of a disk having a hub portion on the shaft 19, and a laterally extending peripheral flange imparting to the driven member a cup shape. The inner wall of the member is provided with a diametrically extending enlargement 21, which is of considerable width. Studs 22 project from the face of the enlargement 21 adjacent to the opposite ends of the latter, and are diametrically opposed. An arm 23 is pivoted 90 on each stud 22. Each arm comprises a relatively flat arcuate member in face engagement with the enlargement 21, and having its outer edge of substantially the same curvature as the inner wall of the driven member 20.

The shaft 19 extends through the driven member 20 and has keyed thereto a cam head 24, of substantially diamond shape,

with diametrically opposed lobes 25, and opposed pairs of contact faces 26 and 27.

A cover plate 28 is fitted against the open side of the driven member 20 to house the mechanism, and has a central hub portion fitting over the end of the shaft 19.

The cam head 24 turns with the shaft 19 within the member 20 and serves as a drive member or part engaging the diametrically opposed inner straight contacting edges 29 of the arms 23, the latter being spaced apart a distance usually greater than the minor axis of the diamond-shaped cam head, and always less than the major axis of the cam head.

Secured in the rim of the driven member, at diametrically opposed points, and extending radially from the member 20, are tubular casings or housings 30, in the inner ends of which are slidably mounted pins or plungers 31, bearing against the outer edges of the arms 23 to urge them inwardly toward the cam head. Tension springs 32 are arranged in the casings 30, as shown in Fig. 2, and are adjustably pressed against the plungers 31 by screw plugs 33, which are threaded into the outer ends of the casings 30.

The cover plate 28 is held in place by screws or bolts 34, which pass through the plate 28 and into the enlargement 21 between the ends of the arms 23, so as not to interfere with the action of the arms.

The plate 28 is utilized for attaching the free end of the connecting rod 14 to the driven member 20. A wrist pin 35 is adjustably secured in any one of a number of openings 36 formed in the plate 28 at different radial distances from the shaft 19, and receives the free end of the connecting rod 14.

In operation, the continuously rotating shaft 19 turns the cam head 24 in the direction indicated by the arrows in Figs. 2, 3 and 4, and in one position brings the contacting faces 27 against the arms 23, as shown in Fig. 3. The spring pressed plungers 31 yield slightly to this contact, and the arms then serve as a means for connecting the drive and driven members. The cam head 24 now carries the driven part 20 from the position shown in Fig. 3 to the position shown in Fig. 4, drawing the connecting rod 14 down and thus lifting the drilling tool. When the connecting rod 14 passes beyond the lower dead center, as shown in Fig. 4, the weight of the well drilling tool quickly rocks the walking beam 12 and lifts the connecting rod independently of the drive member. The driven member 20 now speeds ahead of the drive member 24, and is checked only when the arms 23 reach and come into contact with the faces 26 of the drive member, as shown in Fig. 2.

By adjusting the screw plugs 33 the arms 23 may be advanced to the desired extent against the cam head 24 to vary the phase of the lost motion between the drive and

driven members, and to adjust the tension on the pins 31 to tools of different weights and at different depths in the well.

With the use of this apparatus, the drilling tool is raised slowly by the turning of the shaft, and after the tool is lifted into its highest position the tool is released and permitted to drop by gravity into the well. The tool rests in the bottom of the well until the shaft turns sufficiently to again take up the tool.

What is claimed is:—

1. In well drilling apparatus, a rotatable drive member, a driven member adapted for connection with well drilling tools, adjustable contact elements between the drive and driven members for interlocking the members for rotation as a unit subsequent to the turning of the members relatively to each other, and adjusting means for the contact elements adapted to change the position of the same to vary the range of the movement between the members.

2. In well drilling apparatus, a rotatable drive member having opposed contact faces, a driven member surrounding the drive member and adapted for connection with well drilling tools, and adjustable contact elements on said driven member for alternate engagement with said opposed contact faces to turn the driven member a predetermined distance and raise said well drilling tools, and provide a lost motion between the drive and driven members and permit the tools to drop in the well.

3. In well drilling apparatus, including a walking beam having a connecting rod at one end and a line of tools at its opposite end, a rotatable drive member having opposed contact faces, a driven member concentric with the drive member and adapted for eccentric connection with said connecting rod, and a lost motion connection between said members, said connection being adjustable to vary the range of the lost motion and being resilient to absorb shock incident to the taking up of the connection between the members.

4. In well drilling apparatus, a rotatable drive member having opposed contact faces in its periphery, a driven member mounted for free rotation concentrically about said drive member, adjustable connecting elements carried by the driven member, and means for holding said connecting elements at various distances from said contact faces to vary the limit of the free stroke of the driven member.

5. In well drilling apparatus, including a walking beam having a line of tools on one end and a connecting rod on its opposite end, a rotatable drive member having opposed contacting faces, a rotatably mounted driven member concentric with the drive member, arms hinged at one end upon the driven

- member and lying at the opposite sides of said drive member, and means for advancing and retracting the free ends of said arms toward and from said drive member to vary 5 the distance between the same and the arms.
6. In well drilling apparatus, a rotatable drive member, a driven member concentric with the drive member, a connecting element adjustably mounted on the driven 10 member for engagement with the drive member, and adjustable means on the driven member engaging the connecting element to yieldingly hold it at various distances from the drive member and adjust the length of 15 the free stroke of the driven member.
7. In well drilling apparatus, a rotatable cam head having opposed lobes and having opposed pairs of contact faces at the opposite sides of the lobes, a driven member 20 mounted for rotation about the cam head, and a pair of opposed arms hinged at one end to the driven member and having inner contact faces adapted for alternate engagement with the opposed pairs of said contact 25 faces of the cam head to connect the drive and driven members, and provide lost motion therebetween upon the travel of said arms from one pair of said contact faces of the cam head to the other pair thereof.
- 30 8. In well drilling apparatus, a rotatable cam head having opposed lobes and having opposed pairs of contact faces at the opposite sides of the lobes, a driven member mounted for rotation about the cam head, 35 a pair of arms hinged at one end to the driven member and having inner contact
- faces for alternate engagement with the opposed pairs of the cam head faces to connect the drive and driven members and provide lost motion therebetween upon the 40 travel of said arms from one pair of the cam head faces to the opposite pair thereof, plungers slidably mounted upon the driven member opposite the free ends of said arms, springs mounted on the driven member and 45 engaging the plungers to yieldingly press the latter against the arms, and adjusting means engaging the springs to vary the tension thereof and adjust the arms toward and from the cam head. 50
9. In well drilling apparatus, a hollow driven member, a cam head mounted for rotation in the driven member, a pair of arms hinged at one end in the opposite sides of said driven member, said cam head having 55 pairs of opposed and alternately arranged contact faces lying at obtuse angles to each other, said faces being adapted for alternate contact with said arms to connect the cam head to the driven member and provide lost motion therebetween, and means for adjusting said arms at various distances from said cam head to vary the range of the lost motion. 60

In testimony, that I claim the foregoing 65 as my own, I have hereto affixed my signature in the presence of two witnesses.

ALONZO RUNNION.
